UNITED STATES PATENT OFFICE.

DONALD MCK. HEPBURN, OF NIAGARA FALLS, NEW YORK.

DEVICE FOR SUPPLYING LIQUID TO ENGINE-CYLINDERS.

1,251,371.

Specification of Letters Patent. Patented Dec. 25, 1917.

Application filed February 7, 1916. Serial No. 76,545.

To all whom it may concern:

Be it known that I, DONALD MCK. HEPBURN, of Niagara, Falls, in the county of Niagara and State of New York, have invented certain new and useful Improvements in Devices for Supplying Liquid to Engine-Cylinders, whereof the following is a specification, reference being had to the accompanying drawings.

The most important embodiment, which is contemplated for my invention, is in combination with the cylinder of an internal combustion engine, (especially such as are used in motor cars), for the purpose of priming, cleansing, or lubricating the cylinder.

Broadly speaking, however, the invention relates to a device which is capable of containing liquid and supplying it in controlled quantities to a cylinder whose interior is under relatively high pressure, all external communication with the liquor-container being cut off during the periods of supply to the cylinder, but said container being accessible for replenishing the liquid.

In the accompanying drawings, I have illustrated the device in its preferred form, Figure I, being partly a vertical axial section and partly a view in side elevation indicating by dotted lines a portion of the wall of the cylinder to which it is applied.

Fig. II, is a top or plan view of the device itself.

Fig. III, is an inverted plan view thereof, the representation of the cylinder wall in these last mentioned figures being omitted.

The device comprises a chamber 1, adapted to contain a substantial quantity of the liquid to be supplied, the contour of the wall of said chamber being preferably that of an oblate sphere, as indicated in the cross section of Fig. I. A vertical inlet duct 2, leads upward from the axial region of the chamber 1, and terminates in a funnel-shaped mouth 3. A rotatable valve 4, is seated in the duct 2, so as to open or close communication therethrough, in this instance by the turning of the handle 5.

From the lower axial region of the chamber 1, a vertical discharge duct 6, extends downward and is provided with an external screw thread 7, upon its lower extremity, whereby it may be secured within an aperture 13, in the wall 10, of a cylinder. Said duct 6, is controlled by the rotatable valve 11, manipulated by a handle 12. The bore of said ducts should be such as to permit the

free admission of liquid and attendant displacement of the air or vapor within the chamber, without choking or clogging.

The stems of the valves 4, and 11, may be provided with springs 14, and 15, respectively, to assist the proper seating of the valves.

The operation of the device is as follows:

The valve 11, being closed, and the valve 4, being open, the liquid which it is intended ultimately to introduce into the cylinder for priming, cleansing or lubricating purposes, such for instance as gasolene, is poured in through the inlet funnel 3, until the chamber 1, is properly charged. The valve 4, is then closed.

When it is desired to introduce the liquid into the cylinder, (which is under internal pressure and whose wall is hot), the valve 11, is opened for a brief period, the valve 4, being kept closed. The gaseous, or vaporous medium under pressure within the cylinder immediately forces its way up through the liquid and into the chamber, until the pressure upon the upper surface of the liquid therein is equalized with that within the cylinder. This action is attended by discharge of the liquid into the cylinder, the amount of which can be controlled by manipulation of the valve 11.

It should be noted that since the liquids which practically comprise those intended to be thus introduced are themselves volatile, the result of contact of the incoming liquid with the very hot wall of the cylinder is to instantly convert said liquid into a vapor or gas, thus intensifying the internal pressure within the cylinder and tending to blow out the contents thereof into the chamber 1, until such time as equilibrium of pressure has been restored.

The supply of liquid within the chamber 1, is of course to be replenished in accordance with the demands of the apparatus, this being accomplished by again opening the valve 4, while the valve 11, is closed and charging the chamber as before described.

I have found that by the use of a device of this character, the cylinder of a motor car can be kept substantially free from carbon.

I use the term "engine cylinder", in my claim as comprehending any closed chamber intended to contain gas or vapor, under substantial pressure, and maintained at a relatively high temperature.

Having thus described my invention, I claim:

The combination with an engine cylinder, of a supply device comprising a closed liquid-containing chamber provided with an upper inlet duct and a lower discharge duct; a controlling valve for said inlet duct; a controlling valve for said outlet duct, said liquid-containing chamber having a maximum diameter at a distance above the outlet and the inner wall of the chamber curved continuously in a downward direction from said maximum diameter to said outlet and free

from shoulders whereby the liquid in said chamber will readily flow by gravity into the cylinder when the valve controlling the outlet is opened and the valve controlling the inlet is closed, and means for operating said valves, substantially as set forth.

In testimony whereof, I have hereunto signed my name, at Niagara Falls, New York, this thirty-first day of January 1916.

DONALD McK. HEPBURN.
